CLAIM

The ornamental design for a molecular diagnostic device, as shown and described.

DESCRIPTION

FIG. 1 is a front perspective view of a molecular diagnostic device;

FIG. 2 is a left side view of the molecular diagnostic device illustrated in FIG. 1;

FIG. 3 is a right side view of the molecular diagnostic device illustrated in FIG. 1;

FIG. 4 is a rear view of the molecular diagnostic device illustrated in FIG. 1;

FIG. 5 is a front view of the molecular diagnostic device illustrated in FIG. 1;

FIG. 6 is a top view of the molecular diagnostic device illustrated in FIG. 1; and,

FIG. 7 is a bottom view of the molecular diagnostic device illustrated in FIG. 1.

The broken lines in the figures show disclaimed portions of the molecular diagnostic device and form no part of the claimed design.
